DESIGN FOR A COMBINED MICROPHONE AND AMPLIFIER

Walter H. Huth, Chicago, Ill., assignor to Aurex
Corporation, Chicago, Ill., a corporation of
Illinois

Application May 26, 1937, Serial No. 69,556

Term of patent 14 years

To all whom it may concern:

Be it known that I, Walter H. Huth, a citizen of the United States and resident of Chicago, in the county of Cook and State of Illinois, have invented a new, original, and ornamental Design for a Combined Microphone and Amplifier, of which the following is a specification, reference being had to the accompanying drawing forming a part thereof.

Fig. 1 is a front elevation of a combined microphone and amplifier, showing my new design, a portion of the pedestal being broken away for convenience of illustration.

Fig. 2 is a fragmentary side view of said device.

Fig. 3 is a top plan view of said device.

Fig. 4 is a fragmentary rear view of said device. The device of my design comprises the combined microphone and amplifier shown in solid black lines in the drawing, combined with a base structure shown in dotted lines. The dominant features of the design are shown in the solid black lines.

I claim:

The ornamental design for a combined microphone and amplifier, as shown and described.

WALTER H. HUTH.
